UNITED STATES PATENT OFFICE.

SAMUEL DUSENBURY TOMPKINS, OF JERSEY CITY, NEW JERSEY, ASSIGNOR
TO THE A. A. GRIFFING IRON COMPANY, OF SAME PLACE.

DESIGN FOR A RADIATOR.

SPECIFICATION forming part of Design No. 24,265, dated April 30, 1895.

Application filed March 23, 1895. Serial No. 542,987. Term of patent 14 years.

To all whom it may concern.

Be it known that I, SAMUEL DUSENBURY TOMPKINS, a citizen of the United States, residing at Jersey City, in the county of Hudson and State of New Jersey, have invented and produced a new and original Design for Radiators; and I do declare the following to be a full, clear, and exact description of the same, reference being had to the accompanying drawings, forming a part thereof.

The design is shown in the accompanying drawings, in which—

Figure 1 is a view in perspective of the design on a loop or section of a radiator. Fig. 2 is an enlarged cross-section of the same, and Fig. 3 an enlarged sectional plan view thereof.

This design consists of a radiator loop composed of three parallel or slightly divergent barrels or legs, A, A' A'' united alternately at opposite ends, which form an S-shape and each provided upon each of its opposite sides with three series of flanges or fins a b c, the whole having the configuration shown. The flanges or fins of one series a are in planes substantially parallel with the flanges in which the flanges or fins of the other two series b and c are situated, and the flanges or fins of these other two series b and c are arranged in pairs the members of which are in the same or substantially the same plane. The two series of flanges or fins b and c are so disposed as to leave a space between them extending substantially the length of the barrel or leg, and the flanges or fins of the first named series a are arranged in such manner

as to occupy this space and to alternate with and slightly overlap the flanges of the other two series b and c. The barrels or legs of the loop are substantially ellipsoidal in their cross section, but are preferably provided with oppositely disposed flat surfaces d d'. The middle series of flanges or fins a are situated upon these flat surfaces d d', and the upper edges of the flanges or fins of this series a are practically straight. The upper edges of the flanges or fins of the other two series b and c are curved, the flanges or fins themselves being disposed in whole or in part upon corresponding surfaces of the leg or barrel. A rib e of practically the same height as and joining with the two opposite series of curved flanges or fins b extends substantially from one end of each outside leg or barrel A A'' to the other and is situated upon the outside thereof. These flanges or fins b are arranged so as to alternately intersect the rib e.

The ends of legs or barrels f and f' may be left plain as shown as may also the surfaces around the openings g.

Having thus fully described my device, what I claim is—

The design for a radiator as herein shown and described.

In testimony whereof I affix my signature in presence of two witnesses.

SAMUEL DUSENBURY TOMPKINS.
